THOMAS SHAW, OF HACKENSACK, NEW JERSEY, ASSIGNOR TO AMERICAN TELEPHONE
AND TELEGRAPH COMPANY, A CORPORATION OF NEW YORK

LOADED TRANSMISSION SYSTEM

Application filed November 1, 1927. Serial No. 230,329.

This invention relates to a loaded transmission system, and particularly to one comprising physical circuits having a phantom superimposed thereon, the said phantom being loaded to transmit a frequency or range of frequencies differing from that for which the physical circuits are loaded.

Transmission systems have been devised and used heretofore in which the range of frequencies transmitted by the phantom circuit differs from that transmitted by the physical circuits constituting the sides of the phantom. The patent to Shaw, 1,501,926, which issued on July 22, 1924, discloses a transmission system in which both the phantom circuit and the physical circuits constituting its sides are loaded, the said phantom circuit being used for the transmission of frequencies within the voice range, for example, from 200 to 7500 cycles, and the side circuits for the transmission of carrier frequencies up to, for example, 30,000 cycles. The wide range of carrier frequencies employed, required the loading of the side circuits to be spaced at relatively short intervals, slightly over 900 feet. On the other hand, since the frequency range of the currents transmitted over the phantom circuit was relatively much narrower than that of the sides, the spacing of the phantom circuit loading was equal to six times that of the side circuit loading. Thus, at every sixth loading point upon the side circuits, a phantom loading coil would also be connected with the circuit. As has been pointed out carefully in detail in the said patent to Shaw and also in the patent to Martin and Shaw, 1,501,959 that issued on July 22, 1924, the connection of the phantom windings with the physical circuits at every sixth loading point upon the side circuits introduces a difficulty that can be eliminated only by the use at the phantom-side circuit loading point of a special side circuit coil, namely, one that differs from the other side circuit coils connected with the

same conductors and also of a special phantom coil which differs materially from phantom coils for voice frequency loading where carrier currents are not employed upon the side circuits. Briefly stated, where the range of frequencies transmitted by the side circuits is radically different from the range transmitted by the phantom, it is necessary to employ special loading units at the points where both the side circuits and the phantom circuit are loaded, the side circuit coils of the said unit being different from other side circuit coils employed, and the phantom coil differing from the type of coil that would be employed upon the phantom if carrier currents were not transmitted over the sides. The necessity for providing special coils is undesirable from a manufacturing as well as a service standpoint. It has been found possible to produce a system in which not only may the same side circuit coil be employed in the phantom loading unit as is employed at other points upon the side circuit, but also the same phantom coil may be employed as would be used upon any phantom circuit in which carrier frequencies were not transmitted over the side circuits thereof. My invention resides in such a system.

This invention will be clearly understood from the following description when read in connection with the attached drawing, in which Figures 1 and 2 illustrate the description of the development of the invention; Fig. 2^a represents symbolically the capacities existing in the loaded circuit shown in Fig. 2; Fig. 3 shows a circuit in which the invention is embodied, and Fig. 3^a shows symbolically the capacities existing in the circuit of Fig. 3.

In Fig. 1, L₁ and L₂ represent two circuits that may be employed as the side circuits of a phantom. In the system of the prior art, as exemplified by the said patent to Shaw, the frequency range for carrier transmission was so great that it required the spacing of

the carrier loading coils at a distance of slightly over 900 feet apart. I have found that by reducing the upper limit of the carrier frequency to approximately 13,000 cycles, the side circuit loading coils may be spaced apart a distance that is approximately three times the spacing for the system employing 30,000 cycles as the upper limit; that is to say, the spacing for a cut-off frequency of 13,000 cycles is approximately 2800 feet. Since the spacing of phantom loading coils upon toll entrance cables in which carrier frequencies are not employed upon the side circuits is approximately 6,000 feet, it became apparent that by extending the loading section of the side circuit to 3,000 feet it would be possible to load both the phantom and the side circuits at every other side circuit loading point. By adopting this ratio of spacing of the side circuit coils to the phantom coils, that is to say, a two-to-one ratio, and by arranging the phantom coil windings at the combined phantom-side circuit loading points in the manner hereinafter described, it is possible to employ the same side circuit coil at the phantom-side loading point and also to employ the same phantom loading coil at that point as would be employed upon the phantom circuit of a system in which carrier currents are not transmitted over the sides. The features that render this possible will be apparent from the consideration of Figs. 1, 2 and 2'. Fig. 1 shows the disposition of the side circuit loading coils upon physical circuits which will be assumed to have no phantom circuit superimposed thereon but which could be so used. These coils 1, 2, 3 and 1', 2' and 3', which comprise the windings enclosed within the dotted lines, may be assumed to be spaced approximately 3,000 feet apart. If a phantom circuit were superimposed upon the pairs L_1 and L_2 , and such phantom were loaded in the manner shown by the coils 4 and 5 of Fig. 2, that is to say, by the connection of the coil windings into the side circuits at every other loading point upon the side circuit, the distribution of the capacities between the windings of the side circuit coils, of the phantom coils and between the conductors of each side circuit, would be as shown in Fig. 2'. Assuming as a loading section the distance from the midpoint of the windings at one loading point to the midpoint of the windings upon the same circuit at an adjacent loading point, the capacity of the section A-B would be made up of the capacity a between one-half of the coil 1 at the point A, capacity b representing that between windings 6 and 7 of the phantom loading coil 4, the capacity c representing that of the side circuit conductors between A and B and another capacity a representing that of one-half of the side circuit coil 2 at the loading point B. The next succeeding loading section, namely, that between B and C,

would include the capacity a of one-half of the coil 2 at B, the capacity c of the side circuit between B and C and the capacity a of one-half the coil 3 at the point C. It will be seen, therefore, that the capacity of section A-B differs from that of section B-C by the magnitude of the capacity b . The foregoing statement assumes, of course, that the capacities of the side circuit conductors between A and B and between B and C are equal, which would be substantially so. The introduction of the capacity d into the side circuit A-B causes an impedance irregularity which, through its uniform recurrence, would impair transmission. This difficulty may be remedied in the manner shown in Fig. 3, in which the phantom coil windings are split, one-half being located upon that side of the side circuit loading coil 1 toward the loading point D, and the other half of each of the phantom coil windings being located upon that side of the side circuit loading coil 1 toward the loading point B. Thus, it will be seen in Fig. 3 that the winding 6 of Fig. 2 has been divided into equal halves designated 6' and 6'', and, similarly, the other windings of the phantom loading coil 4' have been divided and connected upon opposite sides of the side circuit coil 1. The same action has been taken with respect to the phantom coil 5' at the loading point C. It will be seen from Fig. 3' showing the capacity distribution of the coils and conductors of Fig. 3 that the capacity of each side circuit is substantially equal to that of every other side circuit, so that no impedance irregularity occurs at any point thereon. If the capacities of each half of a phantom coil winding be represented by b' , the capacity of the loading section A-B comprises the capacities a , b' , c and a . The capacity of the loading section B-C likewise comprises the capacities a , b' , c and a . Since one-half of the loading coil capacity of each phantom loading coil is added to every loading section, it is not necessary to have side circuit coils at the combined phantom-side loading points that differ from the other side circuit coils employed at the points where the phantom is not loaded. It will be apparent that in the system just described the capacity increment of the side circuits due to the connection therein of one-half of the phantom loading coil winding at each combined loading point will occur at opposite ends of adjacent loading sections, that is to say, in the section A-B, it is at the left-hand end, whereas in the section B-C it is at the right-hand end. The position of the capacity increment within the limits of the loading section, however, is not a matter of importance from the standpoint of impedance irregularity.

It will therefore be apparent that by choosing the ratio of spacing of the side circuit loading coils to the phantom loading coils
